[57] CLAIM

The ornamental design for a faucet, substantially as shown and described.

DESCRIPTION

FIG. 1 is a front elevational view of a faucet showing my new design;

FIG. 2 is a left side elevational view thereof;

FIG. 3 is a right side elevational view thereof;

FIG. 4 is a rear elevational view thereof;

FIG. 5 is a top plan view thereof; and

FIG. 6 is a bottom plan view thereof.

The fragmentary broken line representation of a sink top and connecting pipes in FIGS. 1, 2, 3 and 4 are for purposes of illustration only.

FIG. 1

FIG. 2

FIG. 5

FIG. 4

FIG. 3

FIG. 6
